[57] CLAIM

The ornamental design for a “cover with a pocketclip for a telephone handset,” as shown and described.

DESCRIPTION

FIG. 1 is a bottom plan view of a cover with a pocketclip for a telephone handset showing our new design;
FIG. 2 is a front elevational view thereof;
FIG. 3 is a left side elevational view thereof;
FIG. 4 is a rear elevational view thereof;
FIG. 5 is a right side elevational view thereof;
FIG. 6 is a top plan view thereof;
FIG. 7 is a front, bottom and right side perspective view thereof; and,
FIG. 8 is a rear, top, and left side perspective view thereof.
